CALORIE-GRAM COMPUTER ALARM

William L. Carter, 2801 S. Air Depot,
Midwest City, Okla. 73161

Filed Apr. 25, 1966, Ser. No. 1,992

Term of patent 14 years

(Cl. D52—1)

FIG. 1

FIG. 2

FIG. 3

FIGURE 1 is a front perspective view of the calorie-gram computer alarm in operative position, showing my new design;

FIGURE 2 is a rear perspective view; and

FIGURE 3 is a bottom perspective view drawn to a different scale.

The essential features of the design reside in the solid line portions of the drawing, and the pencil is shown for illustrative purposes only.

I claim:

The ornamental design for a calorie-gram computer alarm, substantially as shown and described.
